UNITED STATES PATENT OFFICE.

THEODORE CARTER, OF VALLEY STREAM, NEW YORK.

VAMP EASER.

Application filed April 27, 1927. Serial No. 186,974.

This invention relates to means for stretching the vamp throat of a shoe to adjust it to the individual instep.

An object of the invention is to provide an adjustable tool for stretching the vamp throat of a shoe without altering the size or symmetrical appearance of the shoe.

The invention is particularly adapted for stretching the vamp throat of pumps which 10 comprise a large percentage of all women's shoes. These shoes are made on various patterns such as opera pumps, which employ no fasteners to hold them on the foot, and strap pumps which are held on the foot by 15 means of straps passing over the instep or ankle and fastened by means of buttons, buckles or other fastening devices.

In wearing shoes of this type the edge of 20 the vamp is forced by the foot from its original line and often tends to cut or press on the foot, thereby subjecting the wearer to discomfort ranging from a mild irritation to an excruciating pain in an extreme case. This condition is due partly to the 25 improper design and measurement of shoes and partly to the marked dissimilarity in feet which must be fitted with shoes of standard sizes. Some feet are fleshy while others are thin, and in the bony formation 30 some insteps rise abruptly while others recede from the lines of the shoe pattern.

Heretofore, attempts have been made to 35 relieve the tension at the vamp throat by using ordinary shoe stretchers such as are commonly employed to stretch shoes across the ball region of the vamp. These tools are unsuited for this work because they enlarge the entire vamp and change the shape and symmetry of the shoe before any appreciable stretching is noticed at the vamp 40 throat. As a last resort, shoe dealers sometimes alter the line of the vamp cutting and rebinding or restitching, as the case may be, which at best gives the appearance of a repair job.

The present invention provides a simple and efficient tool for easing the tension at the vamp throat without stretching other parts of a shoe. This tool includes a heel 50 piece which is inserted in the heel seat of a shoe and a stretching block which is inserted under the vamp throat. The stretching block has an inclined front surface which is transversely rounded to conform 55 generally to the contour of the vamp throat.

The stretching block is moved forward by means of an adjusting screw acting between the block and the heel piece. When the stretching block is moved forward it raises the vamp throat and pushes it forward at 60 the same time, thereby stretching it evenly without stretching other parts of the shoe. In its preferred form the tool includes as a third element a stiffening piece which is inserted in the forepart of the shoe to hold 65 down the outersole and provide a smooth elevated sliding surface for the base of the stretching block. The base of the stretching block is preferably shaped to rock on the stiffening piece as it is moved forward. 70

The invention will be described in detail in connection with the accompanying drawing, in which:

Fig. 1 is a longitudinal section of a tool embodying the invention, showing the several parts in normal use in a shoe; and 75

Fig. 2 is a perspective view showing the several parts of the tool in the position in which they are inserted in a shoe.

In the drawing the tool is shown in its preferred form comprising a stretching block 1, a heel piece 2, and a smooth stiffening piece 3 shaped like a half sole. These parts may be made of wood or any other suitable material. The stretching block 1 has a sloping front surface 4 which projects above the vamp throat 5 and recedes sharply in the direction of the ball region of the vamp. The sloping surface 4 is transversely rounded to conform substantially to the contour of the vamp throat. The under surface of the block 1 is preferably tapered in the manner shown to provide a rocking base portion 6. 80

The heel piece 2 comprises a narrow oblong block which is freely insertable in the shoe and is provided with a rounded end 7 adapted to rest against the counter 8 in the heel seat of the shoe. The sides of the heel piece 2 are cut away at 9 to prevent contact with the flexible sides of the shoe. The adjusting mechanism comprises an elongated screw 10 having a threaded end which extends through a nut 11 in the front face of the heel piece 2 and freely enters a chamber 12 which extends longitudinally through the center of the heel piece. The forward end of the screw 10 terminates in a blunt rounded head 13 which is loosely received by a socket 14 in the rear face of the stretching block 110

1. The screw 10 is adjusted by means of an integral thumb piece 15 of any suitable form.

In using the tool to stretch the vamp throat 5 of a shoe the stiffening piece 3 is first placed inside the forepart of the shoe in the manner shown in Fig. 1. The stretching block 1 is then inserted under the vamp throat with the rocking base 6 resting on the smooth upper 10 surface of the stiffening piece 3. The heel piece 2 is then placed in the heel seat of the shoe with its rounded end 7 resting snugly in the counter 8. The thumb piece 15 is grasped with the thumb and forefinger 15 and turned so that the rounded head 13 of the adjusting screw enters the socket 14 and forces the stretching block 1 forward until the desired tension is obtained. The base 20 of the counter 8 at the heel seat of the shoe is very stiff and unyielding in its construction and hence when pressure is exerted on the line a—a of Fig. 1 between the vamp throat and the base of the heel seat the vamp throat must yield. When the adjusting screw 10 is 25 turned in the proper direction the stretching block 1 is moved forward with a slight upward thrust caused by the rocking movement of the block as it slides forward on the stiffening piece 3. The rounded sloping surface 4 of the stretching block 1 is thus wedged underneath the vamp throat and stretches the vamp throat uniformly without distorting the ball region or collar of the shoe. Since no pressure is exerted 30 on other flexible portions of the shoe there is no tendency toward distortion. The stiffening piece 3, in addition to furnishing an elevated smooth sliding surface for the stretching block 1, firmly holds the outer 35 sole of the shoe down as the stretching block is moved forward and thus prevents crushing and wrinkling of the vamp material during the stretching operation.

The features shown but not claimed in 40 this application form part of my co-pending application Serial No. 219,862, filed Sept. 16, 1927, "Vamp easer".

The invention claimed is:

1. A vamp easer comprising a heel piece,

a forwardly tilting easer block formed to 50 engage only the vamp throat and adjusting means having one end cooperating with the heel piece and the other end separate from but adapted to bear against the rear face of said block to move it forward against the 55 vamp while permitting relative movement between the block and the adjusting means.

2. A vamp easer comprising a heel piece, 60 a forwardly tilting easer block formed to engage only the vamp throat and an adjusting screw having one end acting in said heel piece and the other end separate from but adapted to bear against the rear face of the block to move it forward while permitting relative movement between the block and the 65 screw.

3. A vamp easer comprising a block insertable in the forepart of a shoe and having a rocking base portion for supporting it thereon and a front surface shaped to engage only the throat of the vamp and a socket in the rear face of the block, a heel piece insertable in the heel of the shoe, an adjusting screw having one end acting in said heel piece and another blunt and rounded end separate from but adapted to seat against the end of the socket to move the block forward while permitting relative movement between the block and the screw. 70

4. A vamp easer comprising a heel piece, a forwardly tilting easer block formed to engage only the vamp throat, said block and heel piece having recesses in their adjacent faces, a socket member in the recess in said block and a nut in the recess in said heel piece, an adjusting screw cooperating with said nut and extending into the recess in said heel piece, one end of said screw being blunt and adapted to be moved forward and brought to bear against the end of the socket member in said block to move it forward, the engagement of the screw with the block when operated permitting relative movement between the block and the screw. 85 90

Signed at New York in the county of 95 New York and State of New York this 21st day of April A. D. 1927.

THEODORE CARTER.
